UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

DESIGN FOR A VENDING-MACHINE CASING.

Application filed December 30, 1926. Serial No. 20,238. Term of patent 14 years.

To all whom it may concern:

Be it known that I, FRED L. MILLS, a citizen of the United States, residing in Oak Park, in the county of Cook and State of Illinois, have invented a new, original, and ornamental Design for Vending-Machine Casing, of which the following is a specification, reference being had to the accompanying drawing, forming a part thereof.

On the drawing,

Figure 1 is a front elevation of a vending machine casing embodying my new design; and

Figure 2 is a side elevation thereof.

I claim:

The ornamental design for a vending machine casing, as shown.

FRED L. MILLS.
